[57] CLAIM

The ornamental design for a curling iron, as shown and described.

DESCRIPTION

FIG. 1 is a perspective view of the curling iron cover of the new design;

FIG. 2 is a front elevation view of the embodiment shown in FIG. 1;

FIG. 3 is a back elevation view of the embodiment shown in FIG. 1;

FIG. 4 is a side elevation view of the embodiment shown in FIG. 1; and,

FIG. 5 is a top plan view of the embodiment shown in FIG. 1.

The undisclosed sides of the curling iron cover follow the contours of the portions shown.

FIG. 1

FIG. 2

FIG. 3

FIG. 4

FIG. 5
